UNITED STATES PATENT OFFICE.

GUSTAV L. JAEGER, OF NEW YORK, N. Y.

BOX-FASTENER.

SPECIFICATION forming part of Letters Patent No. 251,592, dated December 27, 1881.

Application filed September 24, 1881. (No model.)

To all whom it may concern:

Be it known that I, GUSTAV L. JAEGER, a citizen of the United States, residing at New York, in the county and State of New York, 5 have invented new and useful Improvements in Latches for Boxes, of which the following is a specification.

This invention consists in the combination, with a box, of a latch provided with a lip adapted to catch over the edge of the cover and with an elastic shank which is fastened to the side or front of the box at a point above its bottom end, whereby the elasticity of the shank is caused to retain the lip in its closing position; 10 also, in the combination, with a box, of a latch provided with a lip adapted to catch over the edge of the cover and with an elastic shank which is fastened to the side or front of the box at a point above its bottom end by a pivot on which it can be turned, so that when the box is opened the latch can be turned out of the way; further, in the combination, with a box and with an incline at the edge of the cover, of a latch which is provided with a lip 15 adapted to catch over the edge of the cover and with an elastic shank which is fastened to the side or front of the box, so that when the cover is depressed the incline on its inner edge forces the latch back and permits it to snap over the cover after the same has reached its closing position; also, in the combination, with a box, of a latch which is secured to the side or front of the box, a lip formed on said latch and adapted to catch over the edge of the cover, 20 and a nail-opening in the lip to facilitate the operation of opening the latch.

This invention is illustrated in the accompanying drawings, in which Figure 1 represents a perspective view of a box provided with my latch. Fig. 2 is a transverse section in the plane xx , Fig. 1. Fig. 3 is a perspective view of my latch detached. Fig. 4 is a section similar to that shown in Fig. 2 when a spring-catch is combined with my latch. Fig. 5 is a perspective view of the spring-catch detached. Fig. 6 is a perspective view of a box provided with a modified form of my latch, the latch being closed. Fig. 7 is a similar view when the latch is open.

50 Similar letters indicate corresponding parts.

In these drawings, the letter A designates the front side of a box, and B is the cover, which swings open on a hinge-joint of any suitable construction, and which is retained in its closing position by the latch C. This latch in the example shown in Figs. 1, 2, 3, and 4 is stamped out of elastic sheet metal, and it is provided with a lip, *a*, and two spurs, *b b*, (Fig. 3,) which serve to secure the latch to the front side, A, in such a position that the lip *a* will catch over the edge of the cover B, and that the elasticity of the shank *c* of the latch will retain the lip in its closing position.

By referring to Figs. 2 and 4 it will be seen that the shank *c* extends beyond the point at which the same is fastened to the box, so that the elasticity of the entire shank is brought into action.

Instead of using the spurs *b b* for fastening my latch on the front side of the box, I can use other means—such as a pivot, *b'*, (see Figs. 6 and 7,) which may be clinched on the inside, and which allows the latch being turned to the position shown in Fig. 7, so that it is out of the way when the cover is being opened.

The edge *d* of the cover B is inclined, (see Figs. 2 and 4,) so that when the cover is depressed the lip *a* of the latch is forced back, and then allowed to snap over the edge of the cover as soon as the same has reached its closing position.

In the lip *a* is an opening, *f*, which allows of inserting the nail of the thumb, so as to force the latch back when the cover is to be opened; and in order to prevent the latch from opening spontaneously a spring-catch, D, may be applied to the cover, such as shown in Figs. 4 and 5, said spring-catch being constructed to engage with the opening *f* in the lip of the latch, as shown in Fig. 4. This spring-catch may also be provided with a lip extending over the inclined edge *d* of the cover B, to prevent abrasion of this edge. The latch C may, however, be retained in position simply by driving a tack through the opening *f*, which is of considerable importance when the filled box is to be shipped.

When the cover B is closed the lip *a* of the latch lies flat upon its upper surface, so that it does not interfere with the operation of depressing the cover by means of a press nor

with the operation of piling up a number of boxes or putting them up in a large case or package.

What I claim as new, and desire to secure 5 by Letters Patent, is—

1. The combination, with a box, of a latch provided with a lip adapted to catch over the edge of the cover and with an elastic shank which is fastened to the side or front of the box 10 at a point above its bottom end, substantially as and for the purpose described.
2. The combination, with a box, of a latch provided with a lip adapted to catch over the edge of the cover and with an elastic shank 15 which is fastened to the side or front of the box at a point above its bottom end by a pivot on which it can be turned, substantially as and for the purpose shown and described.
3. The combination, with a box and with an 20 incline formed at the edge of the cover of said

box, of a latch which is provided with a lip adapted to catch over the edge of the cover and with an elastic shank which is fastened to the side or front of the box beneath said incline, substantially as and for the purpose set 25 forth.

4. The combination, with a box, of a latch which is secured to the side or front of the box, a lip formed on said latch and adapted to catch over the edge of the cover, and a nail-opening 30 in the lip to facilitate the operation of opening the latch, substantially as described.

In testimony whereof I have hereunto set my hand in the presence of two subscribing witnesses.

GUSTAV L. JAEGER.
